CLAIM

The ornamental design for a training urinal and commode, as shown and described.

DESCRIPTION

FIG. 1 is a perspective view of a training urinal and commode embodying my new design.

FIG. 2 is a front elevational view thereof.

FIG. 3 is a right side view thereof, the left side view being a mirror image of the right side view.

FIG. 4 is a top plan view thereof.

FIG. 5 is a rear view thereof; and,

FIG. 6 is a bottom view thereof.
